UNITED STATES PATENT OFFICE.

GEORGE FROWEN, OF PLEASANT UNITY, PENNSYLVANIA.

BRAKE ATTACHMENT FOR CARS.

No. 913,719.

Specification of Letters Patent. Patented March 2, 1909.

Application filed October 2, 1908. Serial No. 455,824.

To all whom it may concern:

Be it known that I, GEORGE FROWEN, a citizen of the United States, residing at Pleasant Unity, in the county of Westmoreland and State of Pennsylvania, have invented a new and useful Brake Attachment for Cars, of which the following is a specification.

The object of the invention is to provide a device which may be attached to the ordinary construction of mine car and which will, when in place, provide against travel of the car down a grade up which it is being drawn, should the car coupling break or its members become separated, and will also provide against such movement of an entire train of mine cars should the traction cable break or the cable clutch devices upon the car fail to properly grip the cable. Heretofore, such devices have been usually applied at the middle of the rear end of a car but such an arrangement is unsatisfactory inasmuch as the drag bar, which usually forms an element of such a device, travels along the track substantially midway between the rails thereof and not infrequently strikes the cable and the wheels over which the cable travels either knocking the cable from the wheels or injuring the wheels in some manner. I therefore have as one object of my invention, the provision of a device of this type which may be applied to the end sill of an ordinary mine car at any point along the sill so that the drag bar will travel over the track way between one of the rails and the cable.

Other novel features of the invention will appear in the course of the specific description which is to follow and in the claims.

In the accompanying drawings, Figure 1 is a side elevation of a mine car showing my invention applied thereto, the invention being shown in side elevation and partly in section, and Fig. 2 is a top plan view of the device applied to the car sill.

In the drawings, the car is indicated in general by the reference character A and one end sill of the car by the reference character B, this being the sill to which the device embodying my invention is applied. One of the track rails is shown in Fig. 2 of the drawings and indicated at C, and the cable at D.

The device embodying my invention comprises a body member which is attachable to the sill of the car, and a drag bar which is pivoted to the body member, and said body

member is comprised of a pair of plates 5 provided each with a forward extension 6 at the upper forward corner, and a similar extension 7 at the lower forward corner, the plates being bolted together and held in spaced relation with respect one to the other by spacing blocks of which there are two, one block, namely the upper one, indicated by the numeral 8 being bolted between the upper extension 6 of the said plates 5 and the lower block, indicated by the numeral 9, being bolted between the corresponding extension 7 and the lower corner of the plates. The rear ends of these blocks 8 and 9 terminate directly rearwardly of the forward edges of the plates at which edges the extensions 6 and 7 are formed, and the said extension 6 and the extension 7 together with the blocks 8 and 9 bolted therebetween respectively are arranged to receive between them the end sill B of the car, the extension 6 and block 8 lying above the said sill and the extension 7 and the respective block 9 extending beneath the sill.

The forward edges of the plates 5, when the device is placed upon a car sill, rests directly against the rear face of the sill and the blocks 8 and 9 extend forwardly beyond the plane of the forward face of the sill, the forward end of the block 8 being formed with an opening 10 and in its under side with a recess 11 indicated with the opening, and the corresponding end of the block 9 being formed with keyhole slot 12. A locking pin 13 is inserted vertically through the openings 10 and 12, it being provided at its upper end with a head 14 which rests against the upper face of the end of the block 8, said pin being provided adjacent its lower end with a laterally extending stud 15 adapted to pass through the narrow portion of the keyhole slot, and to lie beneath the block 9 when the pin has been properly inserted. This pin 13 engages with the forward face of the end sill B of the car when the device is in place upon the said sill and, as will be readily understood, prevents accidental displacement of the device.

The rear portions of the upper edges of the plate 5 are preferably inclined downwardly and confined between the plates at the said edge thereof is a block 16 the function of which will be presently more specifically described. The drag bar of the device is indicated by the numeral 17 and at its upper and

forward end extends between the plates 5 beneath the block 16 and is pivoted as at 18 for vertical swinging movement, the lower end of the block being provided with a notch 19 resulting in spurs 20 which are designed to bite into the ties of the track way should the car to which the device is applied start backwardly down the incline. The device is braced against the rear of the sill B by 10 means of angle plates 21 which are carried one by each of the plates 5, one wing of each angle plate resting directly against the rear face of the said sill.

From an inspection of the drawings, it 15 will be seen that in applying the device to the car sill, the pin 13 is raised until its stud 15 seats in the recess 11 in the under side of the upper one of the blocks, when the device may be applied to the sill and the pin 20 dropped to the position shown in Fig. 1 of the drawings, the stud extending below the lower one of the two blocks, the stud serving to prevent accidental disengagement of the pin and also to prevent its complete withdrawal from the device.

As will be observed from the drawings, the block 16 is held rigidly between the side plates of the body member of the device by means of bolts 22, which are passed there- 30 through. One of these bolts 22 is located adjacent the inner or forward end of the block 16, and by removing all of the other bolts 22, the block may be swung upon this bolt as a pivot, so as to provide for greater 35 latitude of movement of the drag-bar 17. By so arranging this block 16 that it may be swung vertically, the device is adapted for application to cars having their end sills located but a short distance above the track- 40 way.

What is claimed is:—

1. The combination with a car sill, of a block formed with portions to extend above and below the sill, a pin passed through the

said portions forwardly of the sill, and a drag 45 bar pivoted to the block.

2. In a device of the class described, the combination with a car sill, of a block provided with portions to extend one above the sill and the other below the sill, a pin passed 50 through the said portions forwardly of the sill, a drag bar pivoted to the block, and means for limiting the upward swinging movement of the said bar.

3. In a device of the class described, the combination with a car sill, of a block provided with portions to extend above and below the sill, a locking means connected with said portions and extending forwardly of the sill, and a drag bar pivoted to the block.

4. In a device of the class described, the combination with a car sill, of a block provided with portions to extend above and below the sill, a pin passed through the said portions, a stud carried by the pin, one of the members being formed with an opening for the passage of the said pin and stud, and the other member with a recess to receive the stud, and a drag bar pivoted to the block.

5. In a device of the class described, the combination with a car, of a block removably secured to the car, and a drag bar pivoted to the block and having a forked lower end, the prongs of the fork being vertically alined.

6. In a device of the class described, the combination with a car, of a block removably secured upon the car, the said block being formed with a recess having a top wall, and a drag bar pivoted at its upper end in the recess, and having its upward swinging move- 75 ment limited by the said wall of the recess.

In testimony that I claim the foregoing as my own, I have hereto affixed my signature in the presence of two witnesses.

GEO. FROWEN.
